(57) **CLAIM**

What is claimed is the ornamental design for a removable rib and wheel assembly, as shown and described.

DESCRIPTION

FIG. 1 is an exploded perspective view of a removable rib and wheel assembly, showing the new design in a first position; FIG. 2 is an alternate exploded perspective view thereof; FIG. 3 is a front elevational view thereof; FIG. 4 is a rear elevational view thereof; FIG. 5 is an exploded left-side elevational view thereof; FIG. 6 is a right-side elevational view thereof; FIG. 7 is a top plan view thereof; FIG. 8 is a bottom plan view thereof; FIG. 9 is an exploded front perspective view thereof; and, FIG. 10 is an alternate front perspective view thereof, illustrated in a second position. The broken lines showing a cooler in FIGS. 1 and 6 are included for the purpose of illustrating the invention in use, and form no part of the claimed design.
